UNITED STATES PATENT OFFICE.

ARCHIBALD BANNATYNE, OF WATERBURY, CONNECTICUT, ASSIGNOR TO
THE WATERBURY CLOCK COMPANY, OF SAME PLACE.

DESIGN FOR A CLOCK-DIAL.

SPECIFICATION forming part of Design No. 18,307, dated May 15, 1888.

Application filed May 3, 1887. Serial No. 237,012. Term of patent 7 years.

To all whom it may concern:

Be it known that I, ARCHIBALD BANNATYNE, residing at Waterbury, in the county of New Haven and State of Connecticut, have 5 invented and produced a new and original Design in Clock-Dials; and I do declare the following to be a full, clear, and exact description of the same, reference being had to the accompanying drawing, which forms a part of to this specification.

The accompanying drawing is a view of my newly-designed clock dial.

The leading feature of my design is a clock-dial bearing upon its face the representation 15 of a steamboat.

The pictured steamboat B is represented as having a walking-beam, C, connecting-rods D D, a smoke-stack, F, from which smoke, J, is seen to be issuing, a paddle-wheel, E, a pad-

dle-wheel box, K, a lower deck, L, and a shorter 20 upper deck, M, each of the decks being provided with windows. Below the paddle-wheel box is an opening, N, in the dial-plate A. Behind the steamboat are represented low lines of bluffs G, sailing craft H, and a light-house, I. 25

I claim—

The design for a clock-dial herein shown and described, the same consisting of a clock-dial bearing upon its face the representation of a steamboat and having an opening in the dial-plate below the paddle-wheel box, as set forth. 30

In testimony whereof I have signed this specification in the presence of two subscribing witnesses.

ARCHIBALD BANNATYNE.
